UNITED STATES PATENT OFFICE.

SATTERLEE ARNOLD, OF NEW YORK, N. Y., ASSIGNOR TO ANNA M. ARNOLD,
OF SAME PLACE.

SEWING-MACHINE.

SPECIFICATION forming part of Letters Patent No. 378,645, dated February 28, 1888.

Application filed May 22, 1886. Serial No. 203,028. (No model.)

To all whom it may concern:

Be it known that I, SATTERLEE ARNOLD, a citizen of the United States, residing at New York, in the county of New York and State of New York, have invented certain new and useful Improvements in Sewing - Machines, of which the following is a specification, reference being had therein to the accompanying drawings.

10 My invention relates to certain improvements in a sewing-machine of the same general character as that shown and described by my Patents Nos. 331,106, 331,107, and 331,108, dated November 24, 1885, the principal object 15 of the present invention being to produce a lock - stitch machine capable of producing "back" or "retrograde" stitches, the advantages of which are more fully set forth in my application, Serial No. 201,084, filed May 20 4, 1886.

In the drawings, Figures 1 and 2 are sectional elevations from opposite sides of my improved machine. Fig. 3 is a plan view, partly in horizontal section. Fig. 4 is a front 25 end view. Fig. 5 is a sectional detail of the horizontal feed-shaft and its lifting device. Fig. 6 is an enlarged detail of a portion of the throat-plate and the feeding-wheel. Fig. 7 is a cross-section of the take-up lever. Fig. 8 is 30 a sectional detail of the lever P and its spring holding-post. Figs. 9 and 10 are diagrams illustrating the retrograde stitch made by my machine. Fig. 11 is a plan view of the work-plate, showing the pivoted shuttle - holder 35 swung outward or forward in position for the insertion or removal of the shuttle. Fig. 12 is a bottom view of the work-plate with the shuttle-holder and shuttle in operative position. Fig. 13 is an end view of the shuttle- 40 holder with the work-plate in section. Fig. 14 is a plan view of the base of the machine, (the work-plate being removed,) showing the looper-rod and its guiding fulerum - block. Fig. 15 is a plan view of the shuttle. Fig. 16 45 is a sectional detail on line 16 16, Fig. 15; and Fig. 17 is a detail view of the shuttle tension-spring and its frictional holding-sleeve.

A denotes the lower part or base of the frame of the machine, and B the bracket-arm 50 thereof.

C is the driving-shaft journaled in vertical bearings in the rear portion of the arm B, said shaft having at its upper end a driving or pulley wheel, c, and at its lower end a crank-disk, c', connected by a link, c'', to a crank-arm, c'', 55 of a short vertical shaft, c', journaled in the post or bracket b, and connected with a looper-rod, W, provided at its front end with a looper, w, for carrying the loops of needle-thread around a stationary shuttle, X, supported beneath the work-plate a by a shuttle-holder, Y, pivoted to said plate.

The shaft c' is out of line with the driving-shaft C, so that it will receive a differential rotary motion from the uniformly-rotating 65 driving-shaft, as in the machine shown by my patents above referred to. The looper-rod W is provided near its center with curved ribs w', embracing a guiding-block, w'', pivoted on a pin, w'', secured to or formed integral with a 70 plate, w', attached to the base A of the machine.

The shaft c' will impart a variable movement to the looper-rod W, as in my prior machine, so that the looper w will move rapidly 75 after it has taken a loop of needle-thread and is spreading the same around the shuttle and slowly while the take-up is tightening the loop to complete the stitch. By providing the looper-rod with the curved ribs embracing the 80 guiding-block w'', so that the fulerum-point or central portion of said rod describes a curved path, the movements of the looper w at the forward end of said rod will be in a circular path, the outer portion of which corresponds 85 to a comparatively large circle and the inner portion to a very small one. Thus the hook or looper can be caused to travel around a horizontally-placed shuttle pointed at one end and adapted to receive at its other end a very 90 large bobbin capable of carrying several times as much thread as the bobbins of many sewing-machines requiring loops of needle-thread as large as mine to encompass the shuttles or bobbins. It will thus be apparent that my 95 looper-rod has a compound movement consisting of three series of movements—to wit, a vibratory movement on its fulerum-pin, a longitudinal sliding movement, and also a slight lateral sliding movement, the latter be- 100

ing due to the curved guide at its central portion formed by the curved ribs w' and the block w^2 , embraced thereby.

The shuttle X is open at its top or upper side, and is supported by a small shelf, y' , attached to or forming part of the pivoted shuttle-holder Y. (See Figs. 11 and 12.) The upper edge of the shuttle is loosely embraced by the holder, so that the loops of needle-thread can be readily carried around the former by the looper w . The work-plate a is provided with a stop or pin, a^4 , arranged to engage a spring-arm, y^2 . (see Figs. 12 and 13,) attached to the shuttle-holder to retain the latter in operative position. Said arm y^2 has a projecting finger piece, y^3 , on which the operator may press to lift the said arm from engagement with the pin a^4 , when the holder will be free to be swung outward, as in Fig. 11, to permit the shuttle to be inserted or removed. It is obvious that the shuttle-holder might be held in place by a stop notch or recess in the work-plate engaged by a projection on the spring-arm y^2 .

25 The shuttle tension-spring x' is attached to a split sleeve, x^2 , tightly embracing the pin x^3 , attached to the shuttle shell or body, said spring pressing directly on the thread of the bobbin x^4 , as in the shuttle shown by my patent, No. 324,351, dated August 18, 1885, and serving also to retain the bobbin within the shuttle. The sleeve x^2 is provided with a nick into which a screw-driver may be inserted for the purpose of turning the sleeve on its pin to 30 adjust the tension or the pressure of the spring x' on the bobbin-thread, or to swing the said spring x' aside to permit the bobbin to be removed or inserted, the said sleeve being frictionally held in any position to which it may 35 be adjusted by reason of its tight fit on the pin x^3 .

It may be observed that the tension-spring x' has a less pressure on the bobbin-thread when the bobbin is nearly empty than when 40 the bobbin is full, owing to the fact that the mass of thread recedes from the spring—or, more properly, from the position originally occupied by the spring—as the thread is unwound from the bobbin, and thus the difference in the varying draft of the thread on the bobbin is automatically compensated for, the thread being drawn off having more purchase on the bobbin when the latter is full than when it is nearly empty, as is well understood. This 45

50 feature is shown in my patent, No. 324,351, dated August 18, 1885; but in the construction shown by the said patent no means are provided for varying the stress of the tension-spring by adjusting the same while in working position.

D is the needle-bar, reciprocating vertically in bearings e , forming part of a swinging frame, E, attached by pivot-screws b' to lugs b^2 at the forward end of the arm B. The needle-bar is 55 or may be reciprocated vertically in the same manner as in the machine embraced by my patents above referred to—that is to say, by a

pitman, d, (operated by an eccentric, e^8 , near the upper end of the driving-shaft C,) primary lever d' , link d^2 , secondary lever d^3 , and link d^4 , connected to the needle-bar by a pin, d^5 , and collar d^6 .

On the shaft C is a worm, c^5 , meshing with a worm-wheel, F, journaled in a small bracket, b^3 , attached to the arm B. This worm-wheel F is provided with a series of face-cams, f , against which bears the toe g of the lever G, pivoted to the arm B and connected by a rod, g' , to the swinging needle-bar frame E. The lever G is preferably provided with a series 80 of holes, g^2 , as shown, so that by attaching the rod g' thereto at different distances from its fulcrum more or less motion may be imparted to the frame E, as may be desired. The toe g of the lever G is held in contact with the face-cams f of the wheel F by a retracting-spring, e' , attached to the frame E and the arm B, the stress of the said spring being imparted to the said lever through the said frame and the connecting-rod g' .

To the hub f' of the cam and worm wheel F is attached a feed-shaft, H, having (in the present instance) its front bearing in a small bracket, h , through which passes a stud, h' , provided at its outer end with the crank-handle h^2 , and having at its inner end an eccentric connection (see Fig. 5) with the arm B, or the plate b^4 attached thereto, so that by turning the said stud by the said handle the bevel gear-wheel h^3 on the forward end of the shaft H may 100 be engaged with or lifted to be disengaged from the bevel gear-wheel i. The said gear-wheel i is attached to the upper end of a vertical shaft, I, supported by a feed hanger or bracket, J, attached to the arm B, said shaft I having 105 at its end a small bevel gear-wheel, i' , meshing with a bevel gear-wheel, k , on the rear end of a shaft, K, supported by the lug j of the bracket J, and the shaft K having at its forward end a gear-wheel, k' , meshing with the 110 feeding-wheel L.

The feeding-wheel L turns on a pin, m , supported by a bracket, M, the rear portion of which is pivoted on the shaft K, said bracket being provided with a projection or lug, m' , 115 against which presses a spring, m^2 , as in Fig. 4, to hold the feeding-wheel in yielding contact with the work-plate. As the said wheel L bears on the throat-plate or work-plate adjacent to the needle-hole therein, it also serves 120 the purpose of a presser-foot.

The bracket M is provided with a handle, m^3 , by which the feed-wheel may be raised or lowered, and the projection or lug m' is squared at its end, so that when the feed-wheel is 125 raised the spring m^2 , bearing against the square end, will hold the said wheel up or away from the work-plate. Thus the said spring is adapted to hold said wheel either in or out of working position.

That portion of the throat-plate which is adjacent to the feed-wheel is made slightly concave (see Figs. 4 and 6) at a' , to correspond to the curvature of the periphery of the said

wheel, or approximately so, thus giving the feed-wheel a longer engagement with the fabric and a stronger hold on the work than would be afforded by a flat throat-plate, and 5 thereby insuring a very strong feed.

The thread from spool N passes through a tension device, O, to an adjustable eye, p, thence to a second tension device, R, thence through an eye, s, on a small arm, S, to an 10 eye, t, in the end of the take-up lever T, whence it passes through a guide-eye, n, to the needle n'. The eye p is carried by a lever, P, pivotally attached to the support o of the tension device O, by the screw p', the free end of the 15 said lever having a small stud, p'', (see Fig. 8,) adapted to engage any one of a series of indentations, u, in the spring-post U, attached to the arm B. Between the tension device O and the stud p the thread is engaged by a pull-off, V, attached to the forward end of the primary needle-bar-operating lever d', to draw from the spool N sufficient thread for each 20 stitch, and by raising or lowering the adjustable eye p the amount of thread thus drawn off from the spool may be varied according to the length of the stitch being made, the amount of thread drawn off being increased by raising 25 said eye and diminished by lowering the same.

The take-up lever T is operated by a cam, 30 c', on the driving-shaft C. As the said lever is a long one, extending from the rear end to the forward end of the machine, it is desirable to have it as light as possible and still sufficiently stiff to prevent it from bending when 35 the machine is running rapidly, and to this end said lever is provided with a longitudinal hollow strengthening-rib, t', as more clearly shown in the detail cross-section, Fig. 7.

The feeding mechanism herein shown and 40 described is continuous in its operation, and is thus, with the needle operating in the usual manner, adapted only for sewing fabrics which will yield somewhat while the needle is in the work, and thus prevent the bending or breaking 45 of the needle.

The needle-bar has a swinging or horizontal movement in the line in which the work is moved by the feed, or approximately so, the horizontal movements of the needle-bar being 50 so timed that they will occur when the needle is out of the work. Although the needle-bar frame E herein shown is a pivoted one, so that the horizontal path actually traversed by the needle is a curved one, yet the needle is so far 55 from the center of movement of the said frame and the arc of its horizontal movement so small that for all practical purposes this horizontal movement may be considered a straight one in the line of the movement of the work. As 60 the work moves continuously forward, it follows that the needle, after having moved to the left in Fig. 4 to make an advance stitch, is moved to the right, same figure, (or toward the operator,) to make a back or retrograde 65 stitch, and as the horizontal movements of the needle are practically in the line in which the work is moved by the feeding mechan-

ism the needle-thread x will be doubled upon itself between alternate pairs of stitches, producing the seam illustrated by the diagrams Figs. 9 and 10, the shuttle-thread y being disposed in the same manner as the needle-thread, as is usual in lock-stitch seams. These back or retrograde stitches give great strength and elasticity to the seam, as fully 75 set forth in my other application referred to, and thus specially adapt it for use in connection with elastic fabrics.

If it be desired to use my machine having the continuous feed for sewing an ordinary 80 straight-ahead seam of lock-stitches in non-elastic fabrics, the connecting-rod g' and the retracting-spring e' may be removed. The vertical movements of the needle-bar will then be imparted thereto in the usual manner, and 85 the swinging frame E, in which the said bar has its vertical bearings, will permit the needle-bar and the needle to be moved horizontally forward, or in the direction of the moving work, while the needle is in the latter, and 90 when the needle leaves the work the swinging frame will be retracted to its first position by the spring e'', connected with the said frame and the arm B, the backward movements of 95 the said frame being arrested by the stop e''. The stress of the spring e'' is so slight as not to impede the forward movement of the needle by the work.

I am aware that it is not new to reciprocate the needle of a sewing-machine horizontally 100 in the line of the movement of the work when the needle is in the goods for the purposes of feeding the same, or for permitting the needle to move with the work when a continuous feed is used; but I believe it to be new to reciprocate the needle of a sewing-machine horizontally 105 in the line of the movement of the work when the needle is out of the goods for forming back or retrograde stitches, as in the machine hereinbefore described.

I do not wish to be understood as limiting my invention to the form of the machine herein shown, as it is obvious that the needle-bar reciprocating horizontally in the line of the feed may, if desired, be used in connection with 110 any of the well-known forms of intermittently-acting feeding devices, as well as with the special form of feeding mechanism which is illustrated and described in the present case.

Having thus described my invention, I claim 120 and desire to secure by Letters Patent—

1. In a sewing-machine, the combination, with a feeding mechanism, of a vertically and horizontally reciprocating needle-bar, the horizontal movements of the said bar being in a 125 line parallel with the line of movement of the work, or approximately so, and timed to occur when the needle is out of the latter, substantially as set forth.

2. In a sewing-machine, the combination, 130 with the work-plate and bracket-arm, of a feeding-wheel above the former, a swinging needle-bar frame, a needle-bar reciprocating vertically in said frame, and mechanism, substantially as

described, for intermittently moving said frame horizontally, said mechanism being constructed and timed, as set forth, to move the said needle-bar horizontally in a line parallel, or approximately so, to that in which the work is moved by the said feeding-wheel and during the intervals when the needle is out of the work.

3. The combination, with the horizontal feed-shaft H, having a gear-wheel at its forward end, the vertically-movable bearing h for the said shaft, and a lifting device for said bearing, of the feeding-wheel and intermediate connecting mechanism between said shaft and wheel, whereby, when the said bearing is lifted, the said gear-wheel will be disconnected from the said intermediate connecting mechanism, substantially as set forth.

4. The combination, with the feed-hanger, the feeding-wheel, and the feed-wheel-operating shaft K, of the supporting-bracket M for the said wheel pivoted upon the said shaft, substantially as set forth.

5. The combination, with the feed hanger or bracket J, of the feed-wheel, the supporting-bracket M, pivotally connected with the said feed-hanger and provided with a projection or lug, as m', and a spring pressing against said projection or lug, and thus adapted to hold the said feed-wheel in or out of working position, substantially as set forth.

6. The combination, with the feed-wheel, of the pivoted supporting-bracket M, carrying the said wheel and having the lug or projection m' and the handle m³, and the spring pressing against said lug and serving to hold the said wheel in or out of working position, substantially as set forth.

7. The combination, with a sewing-machine feeding-wheel, of a throat-plate or work-plate having on its upper side a concave portion curved to correspond to the periphery of the said wheel, or approximately so, whereby the said wheel is enabled to take a strong hold on the work, substantially as set forth.

8. In a sewing-machine, the combination, with a continuously-moving feeding device or wheel, of a loosely-supported needle-bar frame, a light retracting-spring for the latter, and a stop to limit the backward movements of the said frame, under the action of the said spring, whereby, when the needle is in the work, the said frame will be free to follow the movements of the latter, but will be returned to its original position when the needle rises from the work, substantially as set forth.

9. The combination, with the needle-bar-operating lever d', the tension device O, the thread-eye p, and the adjustable lever P, by which the said thread-eye is carried, of the pull-off V, attached to the said needle-bar lever and arranged to act on the thread between the said tension device and the said thread-eye, substantially as set forth.

10. The combination, with the tension device O and its support o, of the lever P, piv-

oted to said support and provided with the thread-eye p, the spring-post U, adapted to hold the said lever in place, and the movable pull-off V, arranged to act on the thread between the said eye and the said tension device, substantially as set forth.

11. The combination, with the take-up lever T, extending from the rear end of the machine to the forward end thereof, and having the longitudinal hollow stiffening rib or corrugation, of the rotating cam for operating the said lever, substantially as set forth.

12. The combination, with the needle-bar and its operating mechanism, of a stationary shuttle, a longitudinally-reciprocating and centrally-pivoted looper-rod having a curved guide near its center, and mechanism for operating said looper-rod, substantially as set forth.

13. The combination, with the pivoted horizontally-swinging shuttle-holder having a shelf or support on which the shuttle can rest horizontally, of the stationary shuttle entirely supported by the said swinging holder, and thereby adapted to be moved in and out therewith, substantially as set forth.

14. The combination, with the work-plate, of the horizontally-swinging shuttle-holder pivoted to the said work-plate, and having a shelf or support on which the shuttle can rest horizontally, and the stationary shuttle entirely supported by the said swinging holder, and thus adapted to be moved in and out horizontally therewith, substantially as set forth.

15. The combination, with the work-plate provided with a stop, as pin a⁴, of a pivoted and horizontally-swinging shuttle-holder having a spring-arm adapted to engage said stop to retain said holder in position, and a shuttle supported vertically by the said holder, substantially as set forth.

16. The combination, with the work-plate having a stop, as pin a⁴, of a shuttle-holder pivoted to said work-plate and provided with a spring-arm adapted to engage said stop and having a projecting finger-piece, substantially as set forth.

17. The combination, with the stationary shuttle and pivoted shuttle-holder, of a looper adapted to travel around said shuttle, a longitudinally-reciprocating and centrally-pivoted looper-rod by which said looper is carried, and mechanism for operating said looper-rod, substantially as set forth.

18. The combination, with a sewing-machine shuttle and a bobbin within the same, of a tension-spring arranged to press on the body of the thread of the bobbin within or between the flanges of the latter, and means for adjusting the tension of the said spring, substantially as set forth.

19. The combination, with a shuttle-shell having an open top or upper side, of a bobbin within the said shell, a tension-spring projecting within or between the flanges of the bobbin, and thus adapted to retain the latter in

the shuttle-shell, and means for adjusting the tension of the said spring, substantially as set forth.

20. The combination, with the shuttle shell or body having the pin x^3 , of the split sleeve x^2 , tightly fitting said pin, and the tension-spring x' , attached to said sleeve, substantially as set forth.

21. The combination, with the needle and its operating mechanism, of a stationary shuttle, a longitudinally-reciprocating and centrally-pivoted looper-rod having a curved guide near its center, mechanism for operating said looper-rod, a looper carried by said rod

to co-operate with the said needle, a take-up lever, and a grooved cam for operating said lever positively in both directions, whereby the take-up lever will be caused to follow the irregular movements of the looper at all times and when the machine is running at high rates of speed, substantially as set forth.

In testimony whereof I affix my signature in presence of two witnesses.

SATTERLEE ARNOLD.
